UNITED STATES PATENT OFFICE

JOHN HENRY DANIELS, OF ST. LOUIS, MISSOURI.

FOLDING TRY-SQUARE.

No. 805,058.

Specification of Letters Patent.

Patented Nov. 21, 1905.

Application filed February 25, 1905. Serial No. 247,331.

To all whom it may concern:

Be it known that I, JOHN HENRY DANIELS, a citizen of the United States, residing at St. Louis, State of Missouri, have invented new and useful Improvements in Folding Try-Squares, of which the following is a specification.

This invention relates to folding try-squares.

10 The objects of the invention are to improve and simplify the construction of such devices; furthermore to increase their efficiency in operation and to decrease the expense attending their manufacture.

15 With the foregoing and other objects in view, which will appear as the description proceeds, the invention resides in the novel combination and arrangement of parts and in the details of construction hereinafter described and claimed as a practical embodiment thereof.

20 In the accompanying drawings, forming a part of this specification, Figure 1 is a plan view of a try-square constructed in accordance with the invention. Fig. 2 is a view looking toward the front edge of the stock. Fig. 3 is a longitudinal section through one end of the stock.

25 Like reference-numerals indicate corresponding parts in the different views.

The reference-numeral 1 indicates the stock, and 2 the blade. These members may be constructed of any suitable material and size. The stock 1 is provided in its rear edge

35 with a leveling-tube 3, a second leveling-tube 4 being arranged at a right angle with respect to the tube 3. Formed in the front edge 5 of the stock 1 is a longitudinal slot 6, having a rearward extension 7 terminating

40 at the rear edge of the stock adjacent to one end thereof, as shown in Fig. 1. The stock 1 is formed on one side of the slot 6 with a recess 8, which preferably is circular in form and is beveled at its outer end, as shown by

45 9. Leading out of the recess 8 is a channel 10, which terminates in a perforation 11, extending through the stock into the slot 6, as shown in Fig. 3. Pivoted mounted in the channel 10, as shown at 12, is a locking

50 member 13, having a pin 14 extending through the perforation 11. At its rear end the locking member 13 is formed with a circular finger portion 15, which is located in the beveled recess 8. Mounted in the recess 8, below the locking member 13, is a spring 16, the free end of which bears against the

under side of the circular finger portion 15 of the locking member 13. The stock 1 preferably is provided on its front edge, adjacent to the slot 6, with scale-marks, as clearly shown in Fig. 2.

The blade 2 is pivotally mounted within the slot 6 adjacent to the rearward extension 7 thereof. At one end the blade 2 is formed with a projection 17, which is adapted when 65 the blade is arranged at a right angle with respect to the stock to fit partially into the rearward extension 7 of the slot 6, as shown in Fig. 1, said projection 17 being arranged to fit but partially into the rearward extension 7, so that the entire edge 18 of the blade 2 may be exposed from one end to the other to facilitate measuring operations. As shown in Fig. 1, both edges 18 and 19 of the stock 2 are provided with suitable scale-marks of any 75 desired kind. The blade 2 is also provided with a longitudinal series of perforations 20, each of which is formed with pointed ends and a circular central portion, as shown in Fig. 1. Adjacent to the pivot-point 21 of 80 the blade 2 a series of perforations 22 is formed in the blade 2, said perforations being placed on the segment of a circle having the pivot-point 21 as its center. The perforations 22 are designed to receive the pin 14 85 of the locking member 13, so as to lock the blade 2 at any desired angle with respect to the stock 1 or to hold the same in alinement therewith when the blade is folded into the slot 6.

90 From the foregoing description it will be apparent to those skilled in the art to which this invention relates that the improved instrument is particularly adapted for use as a try-square, gage, bevel-square, plumb and level, miter-square, rule, and straight-edge.

Changes in the precise embodiment of invention illustrated and described may be made within the scope of the following claims without departing from the spirit of the invention or sacrificing any of its advantages.

100 Having thus described the invention, what is claimed as new is—

1. A try-square comprising a stock having a circular recess formed with a beveled outer end and a channel leading out of said recess, a locking member pivoted in said channel and having a circular finger portion disposed in said recess, a spring in said channel bearing at its free end against the under side of 105 said finger portion, and a blade pivotally connected with said stock and adapted to be 110

held in adjusted position by said locking member.

2. A try-square comprising a stock having a slot in its front edge, said slot at one end of the stock having a rearward extension terminating at the rear edge of the stock, said stock being formed with a circular recess having a beveled outer end, and a channel leading out of said recess and terminating in 10 a perforation extending through to the slot, a locking member pivoted in said channel and having a pin extending through the perforation, said locking member having a circular finger portion located in said recess, a 15 spring in said channel bearing at its free end

against said finger portion, a blade pivoted in the slot of said stock adjacent to said rearward extension and having a projection at one end adapted to fit partially into the rearward extension of said slot, said blade having 20 a series of perforations formed with circular central portions and pointed ends, and a second series of perforations adapted to be engaged by the pin of said locking device.

In testimony whereof I affix my signature 25 in presence of two witnesses.

JOHN HENRY DANIELS.
